Inventor:

Antoine Bonnaz

UNITED STATES PATENT OFFICE.

ANTOINE BONNAZ, OF PARIS, FRANCE.

IMPROVEMENT IN MICROMETER-GAGES.

Specification forming part of Letters Patent No. **141,915**, dated August 19, 1873; application filed May 9, 1873.

To all whom it may concern:

Be it known that I, ANTOINE BONNAZ, of Paris, France, have invented a new and Improved Micrometer; and I do hereby declare the following to be a full, clear, and exact description of the same, reference being had to the accompanying drawing forming part of this specification.

The invention relates to micrometer screw-presses for measuring articles in minute fractions, or with unusual accuracy, and will be first fully described and then clearly pointed out in the claims.

Figure 1 is a side elevation partly broken away; Fig. 2, a vertical section through the axis of screw; Fig. 3, an enlarged view of the abutment-screw and a section of the socket; Fig. 4, a plan view of the same; and Fig. 5, a plan view of the metallic spring-washer that fits between knob and socket.

In the drawing, A represents the frame that supports the screws; B C, the upper and lower screws; and *a a'*, the screw-sockets. The screws are formed with threads, whose section shows an equilateral triangle, and which are reversed in their direction. E is a milled head or knob, swiveled on a screw, G, that is fastened in the head of screw C. D is a plain outer socket, rigidly attached to the screw C, while the knob E has a downward flange, *e*, extending over the upper part *d* of socket. Between the part *d* and knob E is a washer, M, having a series of springs, *m m m*, which produce between the three parts C D E a frictional connection that will cause them to turn together until a resistance is met with adequate to overcome this friction. This spring is seen in detail in Fig. 5 of drawing. *xx* are packing-rings let into annular recesses of sockets D *a* to exclude dust. The socket D' of the

abutment-screw B is made as shown in Fig. 4, being cut diametrically and the two parts clamped together by a screw, V. A numerical circular notation is made upon the movable socket D, and a linear notation on the stationary socket *a*.

The operation is as follows: The abutment-screw B being placed in position to receive the article to be measured, and the article being placed thereon, the knob E is turned with the fingers, when the washer M, having springs *m m m*, will bind the socket D so as to compel the latter and the screw C to turn together until the end *c* reaches the top of the article. The knob will now continue to turn, while the screw C and socket D will stop, the two latter exhibiting a corresponding number in the vertical line marked *o* on the stationary scale. If the article is too small to be reached by the top screw C the abutment B is raised to a greater or less extent.

Having thus described my invention, what I claim as new, and desire to secure by Letters Patent, is—

1. The washer M having the springs *m m m* and the swivel-screw G applied as a connection between the parts C D and knob E in the manner described, to cause them to rotate together until the article is reached, when the screw and socket may stop while the knob continues.

2. The combination, with vertically-notated stationary nut or socket *a* and a stationary support, B, of the screw C and knob E connected by friction, substantially as and for the purpose set forth.

ANTOINE BONNAZ.
